UNITED STATES PATENT OFFICE.

FRANCIS BERNARD FREED, OF WELLINGTON, NEW ZEALAND.

TICKET-DATING MACHINE.

Application filed November 4, 1926, Serial No. 146,249, and in New Zealand November 12, 1925.

This invention relates to machines used in railway booking offices and elsewhere for stamping a date or other mark upon a railway or other ticket or the like, and provides an improved form of machine for the aforesaid purpose.

The principal disadvantage of existing ticket dating machines arises from the fact that the date type is not readily changeable, and there is a certain amount of danger of injury to the fingers of the operator.

The invention will be described as used for a railway booking office. Its use in other booking offices necessitates merely the changing of the type to suit any particular purpose.

The main feature of the machine to be hereinafter described, is the facility with which the type can be changed to enable a ticket to have imprinted thereon any desired date or marking within the range provided by the machine, without unduly delaying the issue of the ticket, thereby enabling a single machine to successfully cope with the expeditious issue of tickets requiring to have imprinted thereon different dates or markings.

A further feature of the invention is the manner in which the imprint or marking is placed on the ticket, the insertion and depression of the latter in a guide provided for its reception causing a hammer to descend and strike the ticket a blow, whereby the latter is forced on to the type and receives an imprint thereon, per medium of an inking ribbon located between said ticket and said type.

According to the invention the improved machine is characterized by the provision of rotatable discs with type on their peripheries, type setting indicators on side extensions from said discs; impression means in the form of a hammer for striking a ticket against selected type in order to receive an imprint of the latter; and means for inking said type.

The extensions from the type discs are in the form of sleeves, the indicators comprising marked bosses fixed on said sleeves, and rotatable below stationary spectacle plates, said sleeves being of different lengths and diameters, and having the indicators secured

on their outer ends, means being provided for preventing the indicators and type discs from rotating except when required.

A depressible ticket guide is mounted over the type discs the depression of said guide actuating the hammer to strike the ticket against the type, said ticket guide and said hammer being mounted on levers eccentrically pivoted in relation to each other, and connected together so that the hammer moves downwards quicker than the ticket guide, for the purpose of striking a ticket inserted in the latter, against the selected type.

The construction and operation of the above mentioned parts, as well as the other parts comprised in the improved machine will be described in detail in conjunction with the accompanying drawing wherein: Figure 1 is a side elevation, Figure 2 a plan view, and Figure 3 a front view of the improved machine while Figure 4 is a longitudinal vertical section thereof, Figure 5 being a vertical section taken lengthways through the type discs and indicators and Figure 6 is a cross sectional view of the latter on the line A—A Figure 5, Figure 7 is a detail view showing means for securing the ends of the inking ribbon to the reels.

The invention is conveniently carried into effect by providing a plurality of discs 1 with the type on their peripheries and separately rotatable by means of indicators 2. Above the type discs 1 is an ink ribbon 20 and above the ribbon 20 a ticket guide 4 and a striking hammer 5 the guide, and the hammer being mounted on the outer ends of levers 6 and 7 respectively.

The type discs 1 are provided with sleeves 8 fitting one upon another, the innermost sleeve 8 passing on a shaft 9, the indicators 2 being fixed on the outer ends of the sleeves 8. The indicators 2 extend laterally from the type discs 1, so that they are convenient to an operator's hands, and clear of the other parts of the machine. The sleeves 8 and shaft 9 are supported horizontally by bearings 10 rising from a base 12. Each indicator 2 comprises a boss with numerals, letters, or words engraved or otherwise marked thereon to agree with the type of the disc 1 to which it is attached, and a

notched flange 2^a. A bar 11 below the indicators 2 and extending from the bearings 10 is fitted with spring operated friction pins or balls 13, adapted to frictionally engage any one of the notches of the flange 2^a with which it is adapted to co-act. Above the indicators 2 is a horizontal stationary spectacle plate 14 extending from the bearings 10 and through which the numbers, letters, or words on the indicators 2, corresponding to the uppermost type of the discs 1, may be read. These indicators 2 are conveniently extended upon each side of the type discs, and on one side there may be indicators 2 to give the date of issue of a ticket, and on the other side indicators 2 to give the date at which a ticket will be available for use on the railway or elsewhere.

The ticket guide 4 has a fence at its sides, a bottom 4^a sloping to a slot 15, and a back 15^a which acts as a stop for a ticket inserting in the guide. This ticket guide is mounted upon the forward end of the lever 6 to the underside of which is fixed a housing 17 for a front ink ribbon reel 18. Another reel 19 is mounted nearer the rear of the lever 6 and an ink ribbon 20 is mounted on the reels 18, 19. The front reel 18, is checked from overrunning by side springs 18^a.

The means for securing the ribbon 20 to the reels 18, 19, consists of small spikes 21 projecting radially from the reel hub and a plate 22 bent to spring over the hub and having holes 22^a corresponding to the spikes 21, so that when the plate 22 is pushed into position on the hub, the spikes 21 perforate the ribbon 20 and pass through said holes 22^a, thus securely holding the ribbon to the reel.

The rear reel 19 has attached thereto a ratchet wheel 23 which is operated by a spring pawl 24 pivoted to the frame 25 wherein the ticket guide lever 6 is mounted, and a gravity detent 26 pivoted upon the fulcrum of the said lever 6 acts as a check to prevent recoil of said reel 19. Both the pawl 24 and detent 26 may be disengaged from the ratchet wheel 23 by means of a double cam 27 operable by means of a spindle 28, and handle 29, from the outside of the frame 25. The front reel 18 being partly open to view, an operator can always see when the ribbon is running out and reverse it.

The hammer 5 comprises a lever 7 pivoted in the frame 25 and normally held in a raised position by a spring 31. The rear end of the hammer lever 7 is connected by a link 32 with the rear end of the ticket guide lever 6, which is further from its fulcrum than is the end of the hammer lever 7, so that said hammer lever when operated by the ticket lever 6, causes the hammer to give a sharp downward blow to a ticket inserted

in the guide 4. The spring 31 returns both the levers 6 and 7, to normal positions, and a stop 33 preferably of wood prevents noise and jar.

A hood 34 houses the rear part of the machine, and with the ticket guide 4, forms a mouthpiece for the insertion of tickets.

In operation, the person in charge places the ticket in the ticket guide 4, against the back 15^a, and depresses the same practically in one operation. The depressing of the ticket guide 4 with its lever 6 operates the hammer lever 7, thereby bringing down the hammer 5, with a sharp blow upon the ticket immediately above the slot 15 in the ticket guide 4. The ink ribbon 20 passes immediately below the slot 15 and the selected type being immediately below the ribbon 20 and slot 15, an impression of the type is made upon the ticket, the type being set in a reverse direction so that the printing on the ticket is in the proper direction.

The person in charge sets his type, readily and quickly to his requirements, and when an alteration is required he has merely to turn an indicator 2 until the desired number, letter or words show through the spectacle plate 14, when the type will have been changed to correspond to the indicator without the machine having been disconnected, or taken apart in any way.

The depression of the ticket guide lever 6 moves the rear ink ribbon reel 19, so that the pawl 24, which is mounted on the frame 25 and is engaged with the ratchet wheel 23, causes the reel 19 to rotate slightly at each depression, and thus intermittently moves the ribbon 20 throughout its length. To return the ribbon 20 to the front reel 18 the double cam 27 is operated by the handle 29 to disengage the pawl 24 and detent 26, and a crank handle 35 on the front reel 18, is then operated to wind back the ribbon 20.

A useful method of using the machine consists in using the indicators 2, on the left hand, to show the date of issue of tickets, a numeral being used for the day of the month, and another numeral for the month of the year; and by using the indicators 2 on the right hand to show the date of availability of the tickets, a numeral being used for the day of the month, the month of the year being represented by the first two letters of the month, and the year by the last two numerals of the year.

Claims:

1. A machine of the character described comprising disks with type on their peripheries rotatable about a horizontal axis, side extensions from said disks, indicators on said extensions, a depressible lever arranged above the type disks, a ticket guide mounted on said depressible lever, a pivoted hammer lever adapted to descend into said guide and actuated by the depressible lever, and means

for passing an inking ribbon between said guide and said type disks substantially as and for the purposes set forth.

2. A machine as claimed in claim 1 where-
5 in the ticket guide is provided with a slot located directly over the selective type, and wherein the hammer descends over said slot substantially as and for the purposes set forth.

10 3. A machine as claimed in claim 1 where-
in the means for passing the ribbon includes a wheel mounted on the forward end of the ticket guide lever, a rear wheel over which the ribbon is passed and mechanism oper-
15 ably connected with the lever and actuatable upon the depressing of said lever substan-
tially as and for the purposes set forth.

4. A machine as claimed in claim 1 where-
in spaced bearings are provided, a horizon-
20 tal shaft journaled in the bearings and on which the disks and the extensions are mounted, the disks being positioned between the bearings, the extensions being in the form of sleeves of different lengths which
25 pass through the bearings and extend there-
beyond substantially as and for the purposes set forth.

5. A machine as claimed in claim 1 where-
in spring actuated catches are engaged with each of the indicators and against which the 30 indicators are rotatable.

6. A machine as claimed in claim 1 where-
in the ticket guide and hammer supporting
levers are pivoted eccentrically in relation
35 to each other, and a link connecting the rear
ends of said levers together so that upon the
ticket guide being depressed the hammer
descends and strikes a ticket which is adapt-
ed to be inserted in said guide.

7. A machine of the character described 40
comprising disks with type on their periph-
eries rotatable about a horizontal axis, side
extensions from said disks, indicators on
said extensions, a depressible member ar-
ranged above the type disks, a ticket guide 45
mounted on said depressible member, depres-
sion means adapted to descend into said
guide and actuated by said depressible mem-
ber, and means for passing an inking ribbon
50 between said guide and said type disks sub-
stantially as and for the purposes set forth.

In testimony whereof I affix my signature.

FRANCIS BERNARD FREED.
